(57) **CLAIM**

The ornamental design for a folding bicycle, as shown and described.

DESCRIPTION

FIG. 1 is a top, front and left perspective view of a folding bicycle in an unfolded position;
FIG. 2 is a top, rear and left perspective view thereof;
FIG. 3 is a front elevational view thereof;
FIG. 4 is a left side elevational view thereof;
FIG. 5 is a bottom plan view thereof;
FIG. 6 is a rear elevational view thereof;
FIG. 7 is a right side elevational view thereof;
FIG. 8 is top plan view thereof;
FIG. 9 is a top, front and left perspective view thereof in a folded position;
FIG. 10 is a top, rear and left perspective view thereof;
FIG. 11 is a front elevational view thereof;
FIG. 12 is a left elevational view thereof;
FIG. 13 is a bottom plan view thereof;
FIG. 14 is a rear elevational view thereof;
FIG. 15 is a right elevational view thereof; and,
FIG. 16 is a top plan view thereof.
